UNITED STATES PATENT OFFICE

153,942

DESIGN FOR A PORTABLE SIGNAL LIGHT FOR MOTOR VEHICLES OR SIMILAR AR- TICLE

Frederick K. Hussey, New York, N. Y.

Application September 18, 1948, Serial No. 148,648

Term of patent 14 years

(Cl. D48—32)

To all whom it may concern:

Be it known that I, Frederick K. Hussey, a citizen of the United States, residing in the Borough of Manhattan, city, county, and State of New York, have invented a new, original, and ornamental Design for a Portable Signal Light for Motor Vehicles or Similar Article, of which the following is a specification, reference being had to the accompanying drawing, forming part thereof.

Fig. 1 is a perspective view of a portable signal light for motor vehicles or similar article showing my new design;

Fig. 2 is a top plan view;

Fig. 3 is a rear elevation;

Fig. 4 is a side elevation; and

Fig. 5 is a front elevation.

I claim:

The ornamental design for a portable signal light for motor vehicles or similar article, substantially as shown.

FREDERICK K. HUSSEY.
